UNITED STATES PATENT OFFICE.

OTTO H. HARTMANN, OF CASSEL-WILHELMSHOHE, GERMANY, ASSIGNOR TO SCHMIDT'SCHE HEISSDAMPF-GESELLSCHAFT M. B. H., OF CASSEL-WILHELMSHOHE, GERMANY, A CORPORATION OF GERMANY.

METHOD AND APPARATUS FOR THE GENERATION OF STEAM.

Application filed March 23, 1925, Serial No. 17,608, and in Germany March 26, 1924.

The invention relates to methods of working movable high-pressure steam generators with water-tube fire-boxes and is specially applicable to locomotives.

5 Movable steam-generating plants fitted with water-tube fire-boxes suffer in general from the disadvantage that scale is found in the water-tubes of the fire-box after a comparatively short working period and as a 10 consequence conduction of heat is unfavourably affected and a troublesome cleaning soon necessitated.

In order to overcome such difficulties, it has already been proposed to utilize the 15 steam generated in the water-tubes of the fire-box, not directly as live steam, but indirectly as a heat-carrier for heating the water in the working boiler. Further difficulties are, however, met with in applying 20 such a method of working to high-pressure steam generators. In such boilers, as only a small space is in general available, it is often not easy, or sometimes not even possible, to arrange in the water space of the 25 working boiler a sufficiently large heating surface for the transference of the heat of the hot steam to the water in the working boiler.

30 The idea underlying the present invention consists in overcoming difficulties of the kind mentioned by simultaneously utilizing both of the known solutions, when possible making use of their advantages and lessening or eliminating their attendant disadvantages.

This result is secured according to the 35 present invention by generating steam by the indirect method of heating in one part of the water-tube fire-box, for example, that part which in general is less accessible for cleaning purposes and generating steam by 40 the direct method of heating in the other part of the fire-box.

45 As regards generation of steam by the direct method, the water tubes forming the side walls of the fire-box can in general be utilized as they can be so arranged from the structural standpoint that their cleaning presents no difficulties. With regard, however, to the water tubes forming the front and rear walls of the fire-box, this is not in 50 general the case; in particular, such tubes are not so readily accessible and are therefore preferably utilized for generating steam by the indirect method.

According to the present invention, steam

may be generated by the indirect method at 55 the same pressure as by the direct method or alternatively at a different pressure. In the first case the steam generated according to the two different methods can either be collected in a common drum or container or, if 60 desired, in different containers connected together. In the second case the steam must be collected in two separate drums or containers.

According to a modification, as applied, 65 for example, to a locomotive boiler having a water-tube fire-box and the usual smoke-tube longitudinal boiler, the heat-transferrers for the heat-carrier may be arranged in the water space of the longitudinal boiler 70 so that the steam produced by the indirect method assists the generation of steam in the longitudinal boiler while the steam produced in the other tubes of the fire-box by the direct method is collected in a special 75 drum arranged above the fire-box.

The design of the water-tube fire-box for carrying out the present invention should also provide for ensuring a good circulation 80 in the water-tubes, for facilitating the cleaning of the tubes by forcing through them the usual tube cleaners and for arranging the tubes so that they serve as a screen to protect the steam-and-water drum against 85 undue temperature stresses.

The accompanying drawings show an illustrative example of a water-tube fire-box for carrying out the present invention, Figs. 1 to 5 being diagrams and Figs. 6 to 8 corresponding constructional embodiments to a 90 larger scale.

Fig. 1 is a longitudinal section through the fire-box;

Figs. 2 and 3 are end views looking respectively on the rear and front wall of the fire-box;

Figs. 4 and 5 show the arrangement of the water-tubes in reference to the steam collector;

Fig. 6 shows a longitudinal section 100 through a constructional form of the fire-box;

Fig. 7 is a cross-section on the line 7—7 of Fig. 6, and

Fig. 8 a cross-section on the line 8—8 of 105 Fig. 6; while finally

Fig. 9 shows a detail.

In carrying the invention into effect ac-

cording to the illustrative form shown in the drawings, the usual longitudinal boiler of a locomotive is indicated at a' , Fig. 6. The rear wall containing the fire-door, b , and the front wall of the fire-box are formed by water tubes, a , which are connected to upper and lower headers, c' and c^2 . The steam generated in these tubes is not utilized directly as live steam but only as a heat-carrier for generating steam which gives up its heat to the water in the boiler. With this object, the upper headers, c' , are connected by pipes, d , for the rear wall and d' for the front wall to the heat transmitters, e , e' ; in the form of serpentines or the like which are arranged in the water space of the upper steam-and-water drum, g , and are connected by pipes, f , f' , to the lower water headers, c^2 . The heated water ascending in the tubes, a , or the steam generated in these tubes thus passes through the pipes, d , d' , into the heat transmitters, e , e' , and there evaporates the surrounding water in the drum, g , the condensate flowing back through the pipes, f , f' , to the lower water chambers, c^2 . The water tubes, h , i , forming the side walls of the furnace are utilized for generation of steam by direct heating, and extend upwards from lower water chambers, q , arranged one on each side of the grate, n , to the steam-and-water drum, g . In order to facilitate the cleaning of these lateral water tubes without the necessity of removing the manhole cover, g' (see Fig. 6) of the drum, on each occasion and entering the drum, g , the tubes h and i , are expanded not directly into the drum, g , but into special intermediate headers k , lying outside the drum, g , which headers are connected with the drum, g , by short lengths of pipe, s , and are provided with openings closable by plugs, m , or the like. (See the diagrammatic views in Figs. 4 and 5 and also Figs. 7 and 8.) In each side wall of the fire-box the uneven-numbered tubes, h , for example, are connected to the intermediate header, k' , lying on the opposite side either directly as in Fig. 4, or by way of intermediate headers k' , see Figs. 7 and 8, while the even-numbered tubes, i , are connected to the intermediate header k on the same side either directly as in Fig. 5, or by way of intermediate headers k' as in Figs. 7 and 8. In this way the tubes, h and i , without having their diameters reduced at the ends, can lie so close together on each side of the boiler that they form continuous side walls. Behind these side walls, that is on the side remote from the furnace, are arranged the tubes, o , between the lower water headers, q , and the steam drum, g , these tubes being protected against the action of the furnace gases by the side walls formed by the tubes, h , i , and therefore serving as downcomers, while the tubes, h and i , serve as risers or evaporating

tubes. The uneven-numbered tubes, h , as shown in Figs. 4 and 8, are so arranged in relation to the drum, g , that they form a protective screen for the latter against the ascending gases and the radiant heat of the furnace. If desired, the space remaining between these crossing tubes, h , may be closed by any suitable refractory material.

In order further to facilitate the cleaning of the water tubes, h , in the construction illustrated by Figs. 7 and 8, the headers k' may be provided with apertures located in line with said tubes and adapted to be closed by plugs, m . The tubes, i , as shown in Fig. 5, can be led to the intermediate header, k , or as in Figs. 7 and 8, into the intermediate chamber, k' , on the same side of the drum, g .

After removal of the plugs, m and m' , the lateral water tubes, h and i , and also the short connecting lengths, s , between the headers, k , and the drum, g , can be readily cleaned by suitable appliances.

As regards the tubes, h , in Figs. 7 and 8, cleaning of those parts of the tubes directed downwards is effected from the headers, k' , and of those parts directed upward from the headers, k .

At the points where the downcomers, o , bend, cross pieces, o' , (see Figs. 7 and 8), are inserted with closable apertures through which the lengths of the tube, o , directed upwards and downwards can be cleaned in the same manner as the risers or evaporating tubes without the necessity of opening the drum, g .

From consideration of strength, the ends of the tubes, h , i and o , expanded into the lower headers, q , and the upper intermediate headers are arranged in staggered relation as shown in Fig. 9.

The water circulation in the side water tubes is thus completed in the following manner:—Downcomers, o , water headers, q , lateral water tubes, h and i , intermediate headers, k' and k , drum, g , downcomers, o .

The high-pressure steam collected in the drum, g , may be led to the high-pressure stage of the engine while the steam for the intermediate and lower stages may be generated in the longitudinal boiler, a' , of the locomotive.

What I claim is:—

1. A boiler having a water-tube fire-box, a drum for steam and water, a heat-transferring device located in said drum but out of communication therewith, said heat-transferring device being in communication with some of the water-tubes of the fire-box so that the water in the drum will be heated by the indirect method of heating through the medium circulating in said heat-transferring device and the water-tubes connected therewith, the other water-tubes having no communication with said heat-transferring

device but being in communication with said drum so as to heat the contents thereof by the direct method of heating.

2. A boiler having a water-tube fire-box,

5 a drum for steam and water, a heat-transferring device located in said drum but out of communication therewith, headers connected with the respective ends of said heat-transferring device and communicating with

10 some of the water-tubes of the fire-box, the other tubes of said fire-box being in direct communication with the interior of the said drum.

3. A boiler having a water-tube fire-box, 15 a drum for steam and water, a heat-transferring device located in said drum but out of communication therewith, upper and lower headers communicating with said heat-transferring device and with some of

20 the water-tubes of said fire-box, to provide a closed circulation path for a heating medium flowing through said heat-transferring device, the other tubes of said fire-box being in direct communication with the interior 25 of the drum to heat the contents thereof by the direct method of heating.

4. In a locomotive boiler having a water-tube fire-box, a drum for steam and water, the water-tubes of the side walls of the 30 fire-box communicating with the said drum and thus being adapted to generate steam in said drum by the direct method of heating, a heat-transferring device located in said drum but out of communication therewith, other water tubes of the front and the rear walls of the fire-box communicating with said heat-transferring device and thus being adapted to generate steam by the indirect method of heating.

40 5. In a locomotive boiler having a water-tube fire-box, a drum for steam and water, the water-tubes of the side walls on the fire-box adapted to generate steam by the direct method of heating, other water-tubes arranged 45 at the front and rear walls of the fire box, headers connected with these other

water-tubes and with a heat-transferring device located in said drum.

6. In a locomotive boiler as claimed in claim 5, water chambers arranged one on each side of the fire-box, the lower ends of the lateral water-tubes communicating with said chambers, the upper ends of these tubes communicating with the drum for steam and water.

50 7. In a locomotive boiler as claimed in claim 5, water chambers arranged one on each side of the fire-box, the lower ends of the lateral water tubes communicating with said chambers, the upper ends of these tubes connected to intermediate headers, said intermediate headers connected to the drum by short lengths of pipe.

60 8. In a locomotive boiler as claimed in claim 5, the lateral water-tubes connected alternately to the same side of the steam-and-water drum and to the opposite side of the drum.

70 9. In a locomotive boiler as claimed in claim 5, the lateral water-tubes connected alternately to the same side of the steam-and-water drum and to the opposite side of this drum, water chambers receiving the lower ends of these tubes, downcomers arranged outside of the continuous wall formed by 75 said lateral tubes, said downcomers connecting the steam-and-water drum and the water chambers.

80 10. In a locomotive boiler as claimed in claim 5, the lateral water-tubes connected alternately to the same side of the steam-and-water drum and to the opposite side of this drum, water chambers receiving the lower ends of these tubes, downcomers arranged outside of the continuous wall formed by 85 said lateral tubes, said downcomers connecting the steam-and-water drum and the water chambers, cross-pieces inserted at the places of bend of said downcomers.

85 In testimony whereof I have hereunto set my hand.

OTTO H. HARTMANN.
